UNITED STATES PATENT OFFICE.

ALINE MULLINIX, OF INDIANAPOLIS, INDIANA, ASSIGNOR TO INDIANAPOLIS CITY HOSPITAL ALUMNI ASSOCIATION, OF INDIANAPOLIS, INDIANA.

NURSE'S CAP.

Application filed June 23, 1927. Serial No. 200,974.

This invention relates to improvements in head dress or coverings, having for an object to provide a highly practical form of cap for wear by nurses when engaged in 5 nursing duties, the construction thereof being such that it is constituted by a single piece of flat material readily foldable into shape for arrangement upon a wearer's head, and which, when soiled, may be returned to its original flat condition and conveniently and effectually laundered as "flat work", the body portion of the cap being 10 free of attachments, buttons or the like, which will tend to render laundering difficult.

It is furthermore an object of the invention to provide a nurse's cap whose construction and design is such as to afford an effectual and practical protection for the 15 hair of a wearer and also, to give a head-dress an artistic design and aesthetic appeal which, by reason of its materially simplified construction may be quickly and conveniently attached and worn with a greater 20 sense of security and comfort.

Other objects of the invention will be in part obvious and in part pointed out hereinafter.

In order that the invention and its mode 30 of operation may be readily understood by those skilled in the art, I have in the accompanying illustrative drawings and in the detailed following description based thereupon, set out one possible embodiment of 35 the invention.

In these drawings:

Figure 1 is a perspective view showing the cap applied to the head of a nurse, and

Figure 2 is a plan view of the same in 40 its flat or unfolded or unflexed position.

Having more particular reference to the drawings, in connection with which like characters of reference will designate corresponding parts throughout, the improved 45 cap may be stated to comprise a flat body portion of suitable material or fabric generally designated by the numeral 1, the material preferably being of a washable material such as white india linen etc., the forward or leading edge of the body portion 50 1 is constituted by several plies or thicknesses of material stitched together as indicated by the numeral 2 whereby to lend greater body to this particular portion of 55 the cap for a purpose which will be subse-

quently described; rows of relatively parallel and longitudinally disposed tucks being stitched or otherwise formed throughout the forward portion of the cap as is indicated by the numeral 3.

Extending transversely and rearwardly from the rearward marginal portion of the body 1 and from its opposite extremities are wing like portions or fingers 4 and 5 having button holes 6, 6^a, 7 and 7^a formed in the free extremities thereof, while from the rearward marginal portion of the body and intermediately of the extensions 4 and 5, another extension or finger 8 is formed, the same being disposed approximately coincidental with the wing-like extensions or fingers 4 and 5 as will be noted upon reference to the Figure 2, this latter extension 8 having longitudinally spaced button holes 9 and 10 formed in the outer or free portion 75 thereof.

At this point, it may be noted that the opposite extremities of the body portion 1 and the opposite marginal portions of the wing like extensions 4 and 5 are curved in 80 the manner illustrated in the Figure 2, whereas the opposite marginal portions of the wing like extension 8 are curved upon themselves whereby to lend a somewhat tapered like formation thereto.

Also, to lend some degree of rigidity or to increase the adjacent portion of the body 1, rows of transversely disposed and relatively parallel tucks or similar folds generally indicated by the numeral 11 are formed in 90 the intermediate portion of the body 1 and are extended longitudinally throughout the length of the intermediate wing like extension 8, said tucks being disposed in relatively opposed pairs whereby to lend to the artistic design or appearance of the cap.

In using or attaching my improved nurse's cap to the head of a wearer, the body portion 1 is flexed upon itself into a substantially semi-circular formation and the transversely disposed wing like extensions 4 and 5 are extended in directions towards each other whereas the intermediate wing like extension 8 is arranged so that the free portion thereof is disposed in substantially over-lapping relationship to the adjacent or meeting ends of the aforesaid extensions 5 and 6. At this time, studs or similar fastening devices are passed through the adjacent or juxtaposed button holes in the extensions 4, 5 and 8, one 105 110

of the studs being passed through the relatively registering button holes 6, 10 and 6^a whereas the remaining stud is passed through the relatively registering button holes 7, 9 and 7^a, thus interconnecting the overlapping and free extremities of said extensions in the manner as is shown in the Figure 1 and providing thereby, a back or rearward portion for the cap. Prior to the folding or flexing of the body portion 1 upon itself, or subsequently thereto, as may be elected by a user of the cap, the two ply forward portion of the body 1 having the longitudinally disposed rows of tucks 3 therein is reversely folded upon itself to that position as is indicated in the Figure 1, thereby providing the cap with the usual band or flap portion 12.

When the cap becomes soiled, it may be quickly and conveniently returned to its original flat condition merely by disengaging the studs designated for convenience herein by the reference character S, from the button holes 6, 7, 9, 10, 7^a and 6^a and at this time, the cap may be laundered conveniently as "flat work", its simplicity of construction assuring effectual laundering and finished appearance thereof.

Manifestly, the construction shown is ca-

pable of considerable modification and such modification as is within the spirit of my claim, I consider within the scope of my invention.

I claim:

A nurse's cap comprising a body of flexible material, the forward portion of said body being straight and the rear portion thereof being cut into a substantially inverted double U shaped formation, the free ends of the extreme extensions of said double U shaped portion adapted to be brought together whereby to carry the sides of said body into close engagement with the sides of the wearer's head, the intermediate extension of said last mentioned portion adapted to lay on the back of the head and receive the meeting free ends of the extreme extensions, the inner marginal edges of said intermediate extension being spaced from the extreme extensions, and a strip of material secured on the straight portion of said body and adapted to fold thereover whereby to maintain said forward portion in close engagement with the head.

In witness whereof I have hereunto set my hand.

ALINE MULLINIX.
